UNITED STATES PATENT OFFICE.

HERBERT T. HERR, OF MERION, PENNSYLVANIA, ASSIGNOR TO WESTINGHOUSE ELECTRIC & MANUFACTURING COMPANY, A CORPORATION OF PENNSYLVANIA.

TURBINE.

Application filed December 15, 1927. Serial No. 240,236.

My invention relates to elastic fluid turbines, and more particularly to means for securing the blading therein, and it has for an object, to improve the construction of apparatus of this character.

In turbine construction, the blades are sometimes secured in circumferential grooves by means of dove-tail, or other similar interlocking connections, the respective 10 grooves being enlarged at suitable points to permit the root portions of the blades to be inserted, one at a time, after which the blades are moved around to their proper positions.

With this type of construction, it is desirable to have a simple, inexpensive and yet very effective means for securing a blade in the enlarged portion of a groove. Also, since the blades, when removed, must be 20 taken out through the enlarged portion of a groove, it is advantageous to have a blade so held in the enlarged portion of a groove that it may be readily removable.

More particularly, therefore, an object of 25 my invention is to provide a turbine of the type described with simple and effective means for securing a blade in the enlarged portion of a circumferential groove, which means shall be so constructed and arranged 30 as to facilitate assembly and removal of the blades.

Apparatus embodying the features of my invention is shown in the accompanying drawings, forming a part of this specification, and wherein:

Fig. 1 is a plan view of a portion of a turbine rotor with the blades removed; and,

Fig. 2 is a longitudinal section of a turbine rotor, taken through an enlarged portion 40 of a circumferential groove therein.

According to my invention, a blade is retained in the enlarged portion of a circumferential groove by pins, or the like, which pass, preferably with a compression fit, 45 through holes provided in the rim of a turbine wheel and the ends of these pins project into recessed portions of the root of a blade. In this way, the pins serve as abutment means for restraining the root portion of a 50 blade.

In Fig. 1, a turbine rotor 10 is provided with a circumferential groove 11 in which the blades are secured. The groove 11 is enlarged at 12 so that the blades may be inserted one at a time and moved around to 55 their proper positions in the groove.

In Fig. 2, a blade 13, of any suitable design, is shown with its root portion 14 secured in the enlarged section 12 of the groove 11. Pins 16, or the like, are forced 60 through holes 17, in the rim of the rotor 10, so that the inner ends of the pins project into the recesses 18 of the root 14 of the blade. These pins 16 preferably fit the holes 17 with a driving fit, and after the inner 65 ends of the pins have been firmly driven against the root of the blade the outer ends of the holes 17 are peened over the outer ends of the pins 16 so as to still further assure that the pins will not become dislodged 70 in operation. The holes 17 are preferably inclined downwardly as shown so as to facilitate the insertion of the pins 16. To remove the blade, it is merely necessary to 75 drill out the pins 16.

While I have shown my invention in but one form, it will be obvious to those skilled in the art that it is not so limited, but is susceptible of various changes and modifications, without departing from the spirit 80 thereof, and I desire, therefore, that only such limitations shall be placed thereupon as are imposed by the prior art or as are specifically set forth in the appended claims.

What I claim is:

1. In an apparatus of the type described, the combination with a rotor having a circumferential groove for retaining the blading therein, said groove having an enlarged portion to permit the blades to be inserted 90 and removed, of a blade root having recesses therein and inserted in the enlarged portion of said groove and pins having their inner ends disposed against the recessed portions of the blade root, said pins being compressed in said rotor.

2. In an apparatus of the type described, the combination with a rotor having a circumferential groove for retaining the blading therein, said groove having an enlarged 100

portion to permit the blades to be inserted and removed, of a blade root having recesses therein and inserted in the enlarged portion of said groove and pins inclined toward the 5 blade root having their inner ends disposed against the recessed portions of the blade root, said pins being compressed in said

rotor, portions of said rotor being peened over the outer ends of said pins.

In testimony whereof, I have hereunto 10 subscribed my name this 7th day of December, 1927.

HERBERT T. HERR.
